RAIL CLEANING DEVICE

Harry G. Foster, Mullens, W. Va.

Application April 24, 1950, Serial No. 157,797

7 Claims. (Cl. 299—31)

1

This invention relates to improvements in rail cleaning devices adapted for use on locomotives for removing any foreign matter directly from the top of the rail in advance of the locomotive wheel.

It has been customary to provide for the discharge of sand on the rails in advance of the locomotive drive wheels, to increase traction between the wheels and the rails. However, when snow and ice collect on top of the rails, the sand may be deflected laterally of the rail and fall to the ground without remaining on the rail when the wheel reaches the sanded portion thereof, whereby the sand serves no effective purpose, and is merely a loss since it cannot provide the desired degree of traction. No satisfactory means has been provided heretofore for effectively cleaning the rail surfaces in advance of the traction wheels, to provide the desired degree of traction between the wheels and the rails by the effective use of sand, where required for that purpose.

One object of this invention is to provide for the effective removal of all foreign matter that may accumulate on the rails in advance of the traction wheels, particularly snow, so as to provide a clean surface for the purpose of getting sand directly on top of the rail in position for effective contact between the wheel and rail.

A further object of the invention is to improve the construction of rail cleaning devices to enable such devices to be made very simply and inexpensively, and to be applied in a practical manner to locomotives without interference with the locomotive structure, and especially the truck or under-carriage of the locomotive.

Still another object of the invention is to provide for the removal of snow and ice from a locomotive rail which would interfere with the traction between the wheel and rail, whether or not sand is applied thereto, by melting and removing the snow and ice if it should accumulate on the rail.

These objects may be accomplished by providing for the removal pneumatically, of any accumulation that occurs on the rail by means of high pressure of air directed onto the top of the rail surface in such relation thereto as to clean the surface of snow or other foreign matter that may accumulate thereon, so as to provide for the application of sand directly on top of the rail. A nozzle may be provided and supported in relatively close proximity to the top of the rail and connected with a source of air under high pressure, so as to direct the air downwardly onto the rail in such relation thereto as to discharge

2

from the rail surface the snow or other foreign matter that may interfere with effective traction between the wheel and rail and allow for the direct contact of sand therebetween.

Because of the presence of snow and ice frequently encountered on rail surfaces, I have provided for the removal of these substances by directing hot air onto the rail surfaces, which will melt the ice and snow and facilitate the discharge thereof by high-pressure air through the nozzle. Moreover, the use of hot air around and adjacent the nozzle will prevent the freezing of moisture in the air, which may otherwise accumulate as ice on the rail, thereby effectively removing all foreign substances from the rail.

Certain embodiments of the invention are illustrated in the accompanying drawings, in which:

Fig. 1 is a side elevation, partly in section, of 20 a portion of a locomotive, showing an application of this invention thereto;

Fig. 2 is a front elevation thereof, partly in section;

Fig. 3 is a cross section through the air duct; 25 Fig. 4 is a longitudinal section therethrough, showing the nozzle in elevation;

Fig. 5 is a side elevation, showing a modification of the invention; and

Fig. 6 is a similar view, partly in section, showing a further modification thereof.

30 The invention is shown as applied to a locomotive, generally designated by the numeral 1, which may be of any suitable form, either steam, diesel or electric, and which is provided with driving wheels 2 mounted on a track comprising rails 3. Provision is made, ordinarily, for applying sand onto the rails 3 in advance of the traction wheels 2, as by means of a sand pipe 4 extending downwardly directly over the rails in front of the traction wheels.

40 I have shown hot air ducts at 5 extending downwardly directly over the respective rails 3 in advance of the sand pipe 4 and driving wheels 2. These air ducts 5 are relatively large pipes, preferably in the form of flexible hose.

45 The ducts 5 are supported by brackets 6 and 7 located, respectively, on the locomotive under-carriage and on the truck shown, with which the wheels 2 are connected.

50 At their upper ends the ducts 5 are connected with a suitable source of hot air. On modern locomotives there are many points from which such hot air may be obtained, as, for instance, the cooling systems of engines, diesel or electric motors, etc. Any of such cooling or other air

systems may be used as a source of hot air, to be connected with the ducts 5, but I have shown for purpose of illustration an electric motor-driven fan, generally designated at 8, provided with a suitable heater or heating means, to supply hot air under relatively low pressure to the ducts. A pressure of between four pounds and five pounds per square inch will be sufficient for this purpose, as an example, without limitation to such specific pressure. Such hot air directed through the ducts 5 will be discharged at the open lower ends of the latter, directly onto the rails 3, and thereby will apply heat sufficient to melt any ice or snow on the rails.

Provision is made also for blowing off snow and foreign substances from the rails, which requires much greater pressure than can be obtained from an ordinary electric motor. However, a source of high pressure air is always available on the locomotive, which can be utilized for this purpose.

I have shown a nozzle, generally designated at 9, extending diametrically across the open lower end of the air duct 5, with one or more orifices 10 in the nozzle 9 to discharge the air therefrom. The nozzle 9 is connected with the lower end of an air tube 11 that extends upwardly through the air duct 5, preferably to a point near the top thereof, with sufficient extent in the duct for heat exchange between the hot air passing through the duct and the air under pressure passing through the tube 11. It is preferred to use a heat conducting material, such as copper, for the construction of the tube 11 and the nozzle 9, to secure an effective heat exchange therebetween, whereby the heat will be transmitted from the air in the duct to the air under pressure in the tube to prevent the freezing of any moisture present in the air. The nozzle 9 and tube 11 are secured in fixed relation to the duct in any suitable manner, as by clamps or other means, generally indicated at 12.

At its upper end the tube 11 is connected through a side of the duct 5 (Fig. 3) with a pipe 13 that extends to a suitable source of air under high pressure, such as a tank 14. A control valve is shown at 15 connected in the pipe 13 in the cab of the locomotive within convenient reach of the engineer.

It will be apparent that upon the opening of the valve 15, air under high pressure will be discharged through the pipe 13 and tube 11 to the nozzle 9, directly onto the rail 3, to remove snow and other foreign matter present on the rail. The valve may be opened just sufficient to provide for a continuous discharge, when needed, thereby effectively removing snow and other foreign matter from the rail in advance of the sand applied at 4 in front of the traction wheels 2.

Since it is practically impossible to keep moisture out of the air held under high pressure of the order of 130 pounds per square inch in the air reservoir 14, and to prevent the freezing of this moisture as the air is discharged at the nozzle 9, it is preferred that hot air be circulated around the nozzle 9 and tube 11, which is accomplished by the location of the nozzle and tube within the enlarged hot air duct 5 leading from a suitable point of hot air on the locomotive, such as the fan 8 that has a suitable heating element for the air. If the ducts 5 are connected with an air cooling system, these may be left in continuous operation without requiring any valve for controlling the action thereof, because the discharge from the air cooling system may be directed

through the ducts without harm, although these ducts may be disconnected from the locomotive during periods of warm weather, or when otherwise not required. When in use, however, the hot air ducts will serve not only to melt snow and ice on the rails, but cooperate with the high pressure air supplied through the nozzle 9 to prevent freezing at the latter, and to warm the high pressure air sufficiently so that the moisture will not condense and freeze on the surfaces of the rails.

The nozzle 9 has a straight discharge edge, as shown in Figs. 3 and 4, within which the opening or openings 10 are located. This discharge side, preferably, is in relatively close proximity to the surface of the rail and extends transversely thereof. However, it may be turned to one side or the other of the rail, as indicated in dotted lines in Fig. 3, so as to direct the discharge either to one side or the other of the rail to deflect the snow or other foreign matter therefrom in either direction, as desired. This may be accomplished by loosening the clamps 6 and 7 and rotating the ducts 5 to the desired extent.

A modification of the invention is shown in Fig. 5, in which the source of hot air to the duct 5a is provided by an air scoop, generally indicated at 16, in open communication with the air duct and extending through or in heat exchange relation with the valve chest 17 of a steam locomotive cylinder, generally indicated at 18. In this way, the air entering the front end of the air scoop 16 will be heated in passing through the scoop and be directed immediately into the upper end of the air duct 5a sufficiently to serve the purpose described above as it passes downward through the air duct. Otherwise, this form of the invention functions in the same manner and for the purpose described above.

A further modification is shown in Fig. 6, in which the air duct is shown at 5b connected with an air scoop 19 open toward the forward end of the locomotive. In this form, however, a heating coil is shown at 20 within the air scoop 19 and may be connected with a suitable source of hot fluid, such as steam, that is available on the locomotive. This heating coil 20 will thereby heat the air passing through the air scoop 19 before it is discharged through the air duct 5b.

In both forms illustrated in Figs. 5 and 6, the air under high pressure is connected with a nozzle mounted within the open lower end of the air duct 5a or 5b, as described above, functioning to remove the snow or other accumulation on the track rails. In the several forms illustrated, there will be provided an effective removal of any accumulation on the rails that would interfere with proper traction between the wheels and the rails, and the effective use of sand therebetween.

While the invention has been illustrated and described in certain embodiments, it is recognized that variations and changes may be made therein without departing from the invention, except as specified in the claims.

I claim:

1. A track cleaner mounted on a vehicle running on track rails comprising means for directing a stream of air under high pressure onto a track rail, and flexible tubular means continuously directing air under low pressure to the rail adjacent the stream of high pressure air.
2. A track cleaner mounted on a vehicle running on tracks comprising a nozzle, a tube connected with the nozzle, and a flexible conduit surrounding the nozzle and tube, said tube being connected with a source of air under high pres-

sure, said nozzle being directed toward said tracks and the conduit being connected with a source of heated air under low pressure.

3. A track cleaner of the character described comprising a nozzle, a tube connected with the nozzle, a flexible conduit surrounding the nozzle and tube, said tube extending lengthwise through the conduit, clamps securing the tube to a side of the conduit, and means mounting the conduit for turning movement of the nozzle relative to the rail to different positions with respect thereto.

4. A track cleaner of the character described comprising a nozzle, a tube connected with the nozzle, a flexible conduit surrounding the nozzle and tube, said nozzle being elongated transversely of the conduit, and means mounting the conduit for turning movement of the nozzle relative to the rail to different positions with respect thereto.

5. A track cleaner of the character described, comprising an enlarged flexible conduit having an open lower end, means mounting the conduit in upright position adapted to be disposed over a rail with said open end in close proximity thereto, a tube extending through the conduit and having a nozzle thereon adjacent the open end of the conduit, said conduit and tube being adapted to be connected with different fluids to be directed thereby onto the rail, and means mounting the conduit for turning movement of said nozzle relative to said rail to different positions with respect thereto.

6. A track cleaner of the character described, comprising an enlarged flexible conduit having an open lower end, means mounting the conduit in upright position adapted to be disposed over a rail with said open end in close proximity thereto, a tube extending through the conduit and having a nozzle thereon adjacent the open end of the conduit, a source of high pressure air connected with the tube, a continuous source of heated air under

low pressure connected with the conduit, and means mounting the conduit for turning movement of said nozzle relative to said rail to different positions with respect thereto.

- 5 7. A track cleaner of the type described, comprising an enlarged, elongated conduit having an open end, said conduit having its other end connected with a continuous source of heated air under low pressure, an elongated tubular metallic element disposed within said conduit, means mounting said conduit for turning movement of said nozzle relative to said rail to different positions with respect thereto, said tubular element having a metallic nozzle at one of its ends and disposed adjacent said open end of said conduit, said conduit surrounding said nozzle, said tubular element having its other end connected with a source of air under high pressure, whereby a continuous heat exchange occurs between said heated air under low pressure in said conduit and said air under high pressure in said tubular element and said nozzle.
